UNITED STATES PATENT OFFICE.

ADAM J. MAY, OF ROCHESTER, NEW YORK, ASSIGNOR TO RITTER DENTAL MANUFACTURING CO., OF ROCHESTER, NEW YORK, A CORPORATION OF NEW YORK.

DENTAL CHAIR.

Application filed April 11, 1924. Serial No. 705,736.

This invention relates to improvements in dental chairs, and has for its object to provide a practical and simply operated chair. A further object of the invention is to provide a chair of this kind with simple motor driven means for elevating the telescoping sections. A still further object of the invention is to provide improved means for moving and controlling the movements of the telescoping sections. To these and other ends the invention consists in certain improvements and combinations of parts all as will be hereinafter more fully described, the novel features being pointed out in the claims at the end of this specification.

In the drawings:

Figure 1 is a vertical sectional view through the base of a dental chair constructed according to my invention and showing the assembled parts in their lowermost position;

Figure 2 is a similar view at substantially right angles to that of Figure 1 and showing the motor driven devices for actuating the telescoping parts.

Figure 3 is a view similar to Figure 2 but showing the parts in different positions.

Figure 4 is a horizontal sectional view taken substantially on the line 4^x—4^x of Figure 2.

Figure 5 is a side elevation of the devices mounted on the base within the inner movable section.

Figure 6 is a plan view of the same;

Figure 7 is a section on the line 7^x—7^x of Figure 5.

Figure 8 is a section on the line 8^x—8^x of Figure 5.

Figure 9 is a side elevation of a portion of the base, parts being broken away to expose the underlying parts.

Figure 10 is a horizontal section through the base and shows the connections between the driving and driven members and means for controlling the same.

Figures 11, 12, 13, 14, 15 and 16 are detail views showing a simple form of clutch mechanism for controlling the operation of the elevating devices.

Similar reference numerals throughout the several views indicate the same parts.

Referring to the drawings, I have shown a hollow base member 1 in which the tele-

scoping members are mounted or housed. The member 1 may be closed at its bottom if desired, and is open at the top as shown. It is substantially circular in cross section and has a central circular depression in its bottom wall 2. Arranged to move vertically within the casing or base 1 and normally seated in the depression in its bottom is an outer telescoping section 3, within which is movably mounted an inner telescoping section 4. Each of said sections are hollow and open at both the top and bottom, the inner section 4 being closed at its open upper end by a chair seat frame 5 of any usual or preferred construction, which is journaled in the upper cylindrical end of said section to rotate thereon, as well understood in the art.

Means are provided for guiding the telescoping sections in their vertical movements.

Said means for the outer section comprises two sets of rollers 6 and 7 arranged in different planes in the base member. Each set of these rollers comprises two pairs, see Figure 4, arranged diametrically opposite each other, and the rollers of each pair are arranged at substantially right angles to each other and are journaled in lugs or ears 8

projecting from the inner wall of the casing 1. The rollers of each pair engage the angularly arranged sides of vertically extending tracks 9 and 10 on the outer section 3. By this arrangement it will be noted that the rollers of each pair oppose each other and that each set of rollers comprises two pairs opposing each other to effectively prevent lateral movements of the section and insure steady even movements thereof.

The inner telescoping section 4 is similarly mounted in the outer section, as will be seen by reference to Figures 3 and 4. Two sets of rollers 12 and 13 being provided and arranged in different vertical planes, each set comprising two pairs of diametrically arranged rollers journaled at substantially right angles to each other in projections 14 on the inner wall of the outer member 3. Each pair of opposing rollers of the set engages opposed sides of a vertical rail or track on the outer wall of the inner section 4.

Mechanical means are provided for elevating the outer member 3 and for simultaneously elevating the inner member on the outer member by which the inner member is carried. To this end there is mounted

55

on the base 2 a standard or frame member 16 having perforated projections or ears 17 at its base by which it is secured in position by means of bolts or other suitable devices. 5 The standard 16 is positioned centrally of the base 2 and projects vertically therefrom into the lower open end of the telescoping member 4 when the latter is in its normal depressed position. The standard 16 is constructed with two opposing parts 18 and 19, see Fig. 8, forming opposed guideways or tracks 20 and 21 between them in which are mounted the vertical toothed members or racks 22 and 23 adapted to reciprocate vertically in the guideways. When in normal depressed position the racks do not extend quite to the plane of the upper surface of the base 2 and at their lower extremities are provided with outwardly extending lugs or 10 projections 24 and 25 which terminate in open slots 26 and 27 in the lower end of the inner telescoping member 4 and at their outer ends may be provided with tapered openings for the reception of screws 28 by means of 15 which in the present instance the racks are secured to the outer telescoping member 3 as clearly shown in Fig. 1. At their upper ends, the parts 18 and 19 are united by a part 29 in the form of a head having a central vertical bearing opening for a purpose presently to be described. Secured to opposite sides of the part 29 by any suitable means, as by the bolts 30, are the members or plates 31 forming with the head, bearing 20 openings for the racks 22 and 23 and in which the racks have a sliding movement. The plates 31 rise vertically above the head 29 and have a block 32 spaced vertically from the head 29 supported between them by means 25 of the bolts 33. Arranged on opposite sides of the racks 22 and 23 and between the head 29 and block 32 and having bearings in the plates 31 are the substantially parallel shafts 34 and 35. Each of the shafts 34 and 35 has 30 a pair of gears 36 mounted thereon to turn therewith and meshing with teeth 37 provided therefore on the racks 22 and 23. Between the gears is provided a worm gear 38 on each shaft 34 and 35. Each of the gears 35 meshes with a driven worm 39 by which the shafts 34 and 35 are driven. It will be understood from the foregoing that when the shafts 34 and 35 are rotated by the worm 39 they revolve in opposite directions to 40 either elevate or depress the racks 22 and 23 simultaneously at a uniform speed and that the outer telescoping member 3 which is secured to the racks is also elevated or depressed. 45 Means are provided for elevating and depressing the inner member 4 relatively to the outer member when the latter is elevated or depressed. To this end, a member 40 in the form of a ring is secured to the upper ends of the racks 22 and 23 by means

of the screws or bolts 41 or any other suitable means. This ring serves to connect the racks to move as a unit and also carries a pair of wheels or pulleys 42 mounted in bearings 43 and 44 on opposite sides of the central opening in the ring. Secured to inwardly projecting lugs 45 in the inner member 4 are flexible members 46 and 47, in the present instance shown as chains, which are led over the pulleys 42 inwardly and downwardly and anchored at their opposite ends in a projection 48 provided therefore in a plug 49 fixed in the block 32 and normally projecting through the central opening in the ring 40. From this construction, it will be noted that when the racks 22 and 23 are elevated to raise the outer section 3, the pulleys 42 are also elevated and the flexible members 46 and 47 move inwardly over the pulleys and raise the inner section to which the outer ends of the flexible members are secured. 50

The plug 49 is threaded into the upper end of a bushing 50 which is threaded into the central opening in the block 32. Seated in the lower end of said bushing and having a bearing therein is the upper end of the shaft 51 to which the worm 39 is keyed or otherwise secured. The lower end of the shaft 51 is somewhat reduced in diameter and extends into an opening in the upper end of an extension 52 of said shaft to which it is keyed. The parts 51 and 52 thus rotate as one and in effect combine to form a single shaft. At its lower end the member 52 is reduced in diameter and has a bearing in a central opening in the base 2. If desired a nut 53 may be threaded on the outer or lower end of the shaft and into a depression provided therefore in the base 2. Keyed on the reduced portion of the shaft 52 and arranged in the central depression in the upper surface of the base 2 is a gear wheel 54, supported to revolve on antifriction bearings as clearly shown in Fig. 1. The wheel or pinion 54 meshes with an idler 55 mounted on the base 2 and this idler in turn meshes with two gears or pinions 56 and 57 also mounted to rotate on the base 2, and operatively connected with motor driven devices. The gears 56 and 57 are keyed to shafts 58 and 59 arranged perpendicularly to the base 2 and having bearings therein and housed in a casing 60 adjacent the base section 1. At their upper ends the shafts 58 and 59 have bearings in a bracket 61, and mounted on said shafts adjacent their upper ends are worm gears 62 and 63. The gears 62 and 63 are loosely mounted on the shafts 58 and 59 and rotate independently thereof, clutch means are provided, however, for selectively connecting one or the other of said gears with its shaft to turn it and with it the gear 56 or 57 mounted thereon. The gears 62 and 63 have downwardly extending hub portions 105 110 115 120 125 130

terminating in enlarged cup members 64 and 65 open at their lower faces. Secured to the shafts within said cup members are devices or blocks 66, best shown in Figs. 12 and 13, which serve as thrust bearings for the gears 62 and 63 which may rotate on the antifriction ball bearings shown, if desired. The cup member 64 forms one part of a friction clutch whereby the shaft is connected with the worm gear to rotate therewith. Each of the blocks 66 is sectioned away on diametrically opposite sides to provide spaces in each of which friction devices are mounted, and slidably held in position by uncut portions 67 on the blocks 66 on which the dogs are supported. In each of said spaces is movably mounted a pair of dogs in the form of blocks 68 having arcuate faces 68a adapted to engage the inner surface of the cup member to connect the cup member and the gear thereon to the block 66 to rotate therewith; when, however, the blocks are released the cup member rotates independently of the block and the shaft on which it is mounted. The members 68 are cut away at their inner ends adjacent each other to form a rectangular space or opening 69. The dogs are cut away at their inner ends to form the inwardly projecting portions 70 of reduced thickness which are engaged and held in position by the projections 67 on the block 66. Movably mounted between the projections 67 and adapted to operatively engage the inner ends of the dogs 68 is an operating member in the form of a rectangular block 72 having a stem 73 projecting downwardly between the projections 67. On its lower extremity, the member 73 is provided with an arcuate crank arm 74. It will be readily understood that there are two sets of these friction devices in each of the cup members 64 and two crank arms 74 which extend through arcs of substantially 90° each and terminate at points substantially diametrically opposite each other. It will be noted that when the actuating devices 72 are positioned with their engaging sides substantially parallel with the diameter of the cup, the dogs or frictional engaging members 68 are permitted to move inwardly toward each other to disengage the cup, if however the free ends of arms 74 are moved outward the blocks 72 are turned on their axes to engage the inner ends of the dogs 68 and move or pry them apart and into frictional engagement with the cup members 64. For the purpose of actuating the arms 74 there is mounted on each of the shafts 58 and 59 for vertical sliding movements into and out of engagement with the free ends of the arms 74 a hub or block 75 substantially hemispherical in form splined to the shaft 58 to rotate therewith and provided with a circumferential groove 76 adjacent its lower end, engaged by diametrically opposite projections 77. These projections are carried at the ends of arms 78 of a yoke 79 swiveled on a rocking arm 80 pivoted intermediate its ends to a support 81. It will be understood that there are two of the hub or actuating members 75 one on each of the shafts 58 and 59, and two of the yokes 79, swiveled on the arm 80 on opposite sides of its pivotal center and at substantially equal distances therefrom. It will be noted that by this construction, when the arm 80 is in a substantially horizontal position, the members 75 are in a neutral position substantially as shown in Fig. 11 with neither of the clutching devices in engaging position. At this time, the gears 62 and 63 may rotate freely on their shafts. When however, the bar 80 is moved on its pivot from this neutral position one or the other of said members 75 moves into engagement with the ends of the arms 74 to actuate the corresponding clutching devices to turn the shaft 58 or 59 to actuate the devices for elevating or depressing the telescoping members. If desired, the inner engaging ends of the arms 74 may be provided with antifriction bearings 82, as shown in the drawings.

Means, under control of the operator, are provided for rocking the arm 80 in one direction or the other. Said means comprises an arm or extension 83, Fig. 9, secured to one end of the arm and extending upwardly therefrom. To the upper end of the extension 83 is pivotally connected an arm 84 of a bell crank lever 85 pivotally mounted in the supports 86 projecting from the bottom 2 of the base section. The other arm 87 of the bell crank extends downwardly from the pivot and at its lower end is pivoted to the end of a rod or link 88. At its other end, the rod 88 is pivoted in ears 89 projecting from a rock shaft 90 mounted in projections 91 on the bottom 2. Extending in opposite directions from the rock shaft 90 are arms 92 and 93 and extending upwardly from the ends of said arms and through openings provided therefor in the base section, are operating members 94 and 95 having their upper outer ends offset laterally and enlarged as at 96 and 97 to be engaged and operated conveniently by the foot of the operator. To retain the parts in normal neutral position, expansion springs 98 and 99 may be coiled about the members 94 and 95 between the arms 92 and 93 and the wall of the base section. From this construction, it will be noted that when the arm 92 is depressed, the arm 84 of the bell crank 85 will swing downwardly to depress the adjacent end of the rock arm 80 and elevate the opposite end to actuate the clutch devices to connect the gear 63 to the shaft 59. When however the arm 93 is depressed, the arm 84 of the bell crank is elevated and also the

adjacent end of the rocking arm 80 to actuate the clutch devices to connect the gear 62 to the shaft 58 to rotate the same. When released the parts will be returned to the 5 normal neutral position by the action of the springs 94 or 95.

I have shown the driving member or worm 64^a connected directly with the shaft of a motor, in the present instance an electric 10 motor 100, and have provided means for automatically closing the circuit of the motor when either clutch is actuated to rotate a shaft 58 or 59. Said means comprises a pivoted switch member 101 movable from a 15 normal central neutral position shown in Fig. 9 into engagement with one or the other of the contact members 102 and 103, said switch having constant sliding engagement with the contact member 104. Mounted on 20 the arm 84 of the bell crank is a link 105 loosely connecting said arm with an arm 106 connected with the switch 101 and projecting from its pivot. When the arm 84 is elevated the switch 101 is moved to the right into 25 engagement with the contact 102 to close the circuit through the contacts 104 and 102 and when the arm 84 is depressed the switch 101 is moved to the left into engagement with the contact 103 to close the circuit through 30 the contacts 104 and 103. From an inspection of the drawings it will be noted that rotation of the worm 64^a operates to turn the gears 58 and 59 in opposite directions, which motion is transmitted to the gears 56 and 57 through the operation of the clutch 35 devices and to the gear 54 through the gear 55. The gear 54 being rotated in one direction or the other to elevate or depress the telescoping sections through the gears 34 and 40 35 as one or the other of the clutches is thrown into operation to turn the gear 56 or the gear 57 in the reverse direction.

Means are provided for automatically returning the parts to normal neutral position 45 when the outer telescoping member approaches the extreme of its movement in either direction. Said means comprises a rod 107 having a saddle 108 at its lower end provided with an inclined slot 109. The 50 saddle 108 is arranged on the rod 88 which has a pin 110 projecting into the inclined slot in the saddle. At its upper end, the rod 107 is enlarged as at 111 and slidably fits in an eye 112 projecting from the wall 55 of the outer telescoping member. When the rod 88 is moved to the right in Fig. 9, the clutch devices are thrown into operation to drive the shaft 59 and gear 57 to elevate the telescoping sections. During the elevating 60 movement the eye 112 moves along the rod 107 and engages the enlargement 111 at the upper end of the rod as the telescoping members approach the limit of their upward movement and pulls the rod 107 upward, the 65 edges of the slot 109 operating on the pin

110 to cam the rod 88 to the left in Fig. 9 to return the parts to normal neutral position. When the rod 88 is moved to the left to reverse the operation, the eye or ring 112 rides down the rod 107 as the telescoping sections are depressed until the limit of their downward movement is approached when a lug 113 projecting from the outer telescoping member engages the upper end of the rod 107 and depresses it. This action cams the rod 88 to the right and again returns the parts to normal neutral position. With the parts in the position shown in Fig. 9 in which the telescoping members are in depressed position the bar 88 is locked against 80 movement to the left and the pedal 97 against depression to start the motor and close the clutch to actuate the parts to further depress the telescoping members through the engagement of the rod 107 with the lug or stop 113. Similarly when the telescoping members are in extreme elevated position, the engagement of the ring or loop 112 with the enlarged upper end of the rod 107 locks the bar 88 against movement to the right and the pedal 96 against depression to operate the parts for further elevation which may cause injury thereto. The telescoping parts may be brought to rest at any intermediate point by releasing the pedal which is being depressed and permitting the spring 98 or 99 to return the parts to normal 95 neutral position releasing the engaged clutch and throwing out the switch to stop the motor when in elevated position the inner telescoping member 4 is supported on the outer member 3 by means of the flexible members 46 and 47 and the outer member 3 is supported on the racks 22 and 23 and actuating devices therefore. 100

I claim as my invention:

1. In a chair base, the combination of a base member, inner and outer telescoping members movable therein, rack and pinion devices operating within the telescoping members to elevate or to depress the same, a standard projecting within the inner telescoping member and forming a support for the pinion and a guide for the rack, motor driven means for actuating said rack and pinion devices, an operating connection between the standard and inner telescoping member and means for controlling said motor driven means. 110

2. In a chair base the combination of a base member, a standard projecting longitudinally within the base member, a telescoping member movable within the base member, a rack projecting within and guided by said standard and connected with said telescoping member and adapted to raise the latter, a pinion engaging said rack, motor driven means for actuating said pinion, a second telescoping member within the first and a flexible operating connection having 120 125 130

one end connected with the standard and the other with the second mentioned telescoping member.

3. In a chair base, the combination of a base member, a telescoping member movable therein, a rack disposed within and connected with said telescoping member adapted to raise the latter, a pinion engaging said rack, a standard projecting longitudinally within the telescoping member for guiding the rack, a shaft projecting within the standard for actuating said pinion and means for driving the shaft.

4. In a chair base, the combination of a base member, a telescoping member movable therein, a standard projecting longitudinally within the telescoping member, a rack movable upon the standard and having teeth on opposite edges thereof and being disposed within and connected with said telescoping member, pinions engaging the teeth of said rack and operative to move the rack longitudinally within the base, motor driven means for actuating said pinions, and means for controlling said motor driven means.

5. In a chair base, the combination of a base member, a telescoping member movable therein, a standard projecting longitudinally within the telescoping member, a pair of racks movable upon the standard and having oppositely arranged teeth and being disposed within and connected with said telescoping member, a pair of pinions engaging each rack, a pair of shafts revolvably supported on the base member on each of which a pinion of each pair is mounted, motor driven means for driving said shafts, and means for controlling said motor driven means.

6. In a chair base, the combination of a base member, a telescoping member movable therein, a pair of racks disposed within and connected with said telescoping member for raising the latter, a standard on the base member within the telescoping member having guides in which said racks are movable, pinions engaging said racks, shafts revolvble in said standard and carrying said pinions, motor driven means comprising a worm and gear for driving said shafts and means for controlling said motor driven means.

7. In a chair base, the combination of a base section, an outer telescoping section movably mounted therein, an inner telescoping section movably mounted in the outer telescoping section, means for moving the outer telescoping section on the base section and means for moving the inner telescoping section relatively to the outer section when the latter is moved, said means comprising a flexible member terminating at one end within the inner telescoping section and being secured thereto and to a fixed support within the inner section at its opposite end and a pulley disposed within the inner sec-

tion and movable with the outer section and over which the flexible member moves.

8. In a chair base, the combination of a base section, an outer telescoping section movably mounted therein, and inner telescoping section movably mounted in the outer telescoping section, means for moving the outer telescoping section on the base section and means for moving the inner telescoping section relatively to the outer section 75 when the latter is moved, said means comprising a pair of flexible members each terminating at one end within the inner telescoping section and being secured thereto and to a fixed support within the inner section at its opposite end and a pair of pulleys disposed within the inner section and movable with the outer section and over which the flexible members move.

9. In a chair base, the combination of a base section, an outer telescoping section movable therein, an inner telescoping section movable in the outer telescoping section, means for moving the inner section relatively to the outer section when the latter is moved, and motor driven means for moving the outer section, said means comprising a pair of movable racks rigidly connected with the outer section for moving the latter and normally arranged within the inner section and being disposed independently thereof to move relative thereto, pinions engaging said racks and driving means for the pinions.

10. In a chair base, the combination of a base section, an outer telescoping section movable therein, an inner telescoping section movable in the outer telescoping section, means for moving the inner section relatively to the outer section when the latter is moved, 105 a standard normally projecting into the inner section from the base, a pair of connected racks movable in said standard and connected with the outer section, pinions revoluble in said standard and engaging said 110 racks to move the outer section, and a worm for driving said pinions arranged on a vertical axis in said standard.

11. In a chair lift mechanism, the combination of a base, a column mounted for movement upon the base, a support within the base projecting within the column, a rack slidably mounted upon the support and connected with the column to move the latter, and means operatively connected with the rack including a pinion and a shaft extending longitudinally within the column and having a gear adapted to drive the pinion.

12. In a chair lift mechanism, the combination of a base, a column mounted for movement upon the base, a support extending longitudinally within the base, a rack slidably mounted upon said support and operatively connected with the column, a 130

- pinion carried by said support and engaging the rack, a shaft disposed longitudinally within the support and operatively connected with the pinion, and operating means for the shaft.
13. In a chair lift mechanism, the combination of a base, a column mounted for movement upon the base, a standard within the base, a rack slidably mounted upon the standard and having a lateral extension engaging the column, a gear journaled upon the standard and engaging the rack, a longitudinally disposed shaft within the base operatively connected with said gear, and means for driving the shaft.
14. In a chair lift mechanism, the combination of a base, a column mounted for movement upon the base, a standard projecting within the base, a pair of racks slidably mounted upon the standard and operatively connected with the column, a shaft journaled upon the standard having pinions meshing with the racks, a gear upon said shaft, and a drive shaft operatively connected with said gear.
15. In a chair lift mechanism, the combination of a base, a column mounted for movement upon the base, a second column movable relatively to the first, a fixed support within the base, a rack slidably mounted upon said support and operatively connected with the first mentioned column, means actuated by the rack adapted to move the second column relatively to the first, and means operatively connected with the rack.
16. In a chair lift mechanism, the combination of a base, an outer section mounted for movement upon the base, an inner section, a track supported within the inner section, a rack slidably upon the track and operatively connected both with the inner and outer sections for moving one relative to another, and means operatively connected with the rack.
17. In a chair lift mechanism, the combination of a base, a column mounted for movement upon the base, a second column movable relative to the first, a fixed support projecting within the first mentioned column, a flexible connection between the support and the second mentioned column, a device movable vertically upon the support and adapted to raise the first mentioned column and also arranged to cooperate with said flexible member to raise the second men-
- tioned column, and means for moving said device upon the support.
18. In a chair lift mechanism, the combination of a base, a column movable within the base, a second column movable within the first, a standard projecting upwardly within the base, a flexible connection between the standard and second mentioned column, a rack slidably mounted upon the standard and operatively connected with the first mentioned column, means carried by the rack adapted to engage said flexible connection whereby to raise the second mentioned column, and means for actuating the rack.
19. In a chair lift mechanism, the combination of a base, a column mounted for movement upon the base, a second column movable within the first, a standard projecting upwardly within the base, a pair of flexible connections between the standard and the second mentioned column, a pair of racks slidably disposed upon said standard, pulleys carried by said racks and engaging said flexible connections whereby to move the second mentioned column, and operating means for the racks.
20. In a chair lift mechanism, the combination of a base, a column movable therein, a second column mounted for movement within the first, a standard projecting upwardly within the base, slidably mounted means upon the standard connected with the first mentioned column for moving the latter, means operatively connecting said slidably mounted means with the second mentioned column, and a shaft projecting within the base and operatively connected with said slidably mounted means.
21. In a chair lift mechanism, the combination of a base, a column movable therein, a second column movable within the first, a standard projecting upwardly within the base into said columns when the latter are in lowered position, a member slidably mounted upon the standard and operatively connected with the first mentioned column, means interposed between the standard and the second mentioned column with which said slidably mounted members is adapted to cooperate whereby to move the second mentioned column, and means for actuating said slidably mounted member including a shaft and gearing driven thereby.

ADAM J. MAY.
